UNITED STATES PATENT OFFICE.

LEE SPRINGER, OF HARDIN, MONTANA.

COMBINATION-TOOL.

1,293,966.

Specification of Letters Patent. Patented Feb. 11, 1919.

Application filed April 28, 1917. Serial No. 165,251.

To all whom it may concern:

Be it known that I, LEE SPRINGER, a citizen of the United States, residing at Hardin, in the county of Big Horn and State of 5 Montana, have invented certain new and useful Improvements in Combination-Tools, of which the following is a specification.

My invention relates to combination tools.

The object of my invention is to produce a 10 combination nail and staple driver, nail and staple puller, wire tightener and wire cutter, arranged in convenient and compact form; and a further object of my invention is to produce a more simple, cheap, and efficient 15 device of the character described than has heretofore been attained.

To these ends, my invention includes a combination and arrangement of component parts to be hereinafter described and more 20 particularly pointed out in the claims.

In the accompanying drawings, in which like reference characters indicate similar parts,

Figure 1 is a side view of my device in 25 closed position;

Fig. 2 is a similar view in open position; and

Fig. 3 is a perspective view of the pivoted parts disassembled.

30 My invention includes generally a pair of pivoted members, each of which is provided with a longitudinal shank on one of which is provided a head for driving nails or staples, and on the other of which is provided 35 a claw for pulling nails and staples; a cutting blade carried on the shank of one of the pivoted members and a recess provided on the opposite shank registering with the cutting blade; a longitudinally extending 40 projection on the outer end of each pivoted member adapted to coöperate with each other to form a clamping plier, said extensions being provided with longitudinal and trans- 45 verse registering grooves for gripping a wire.

45 Referring now to the drawings, 1 indicates a pivoted member having a shank portion 2, and an annular plate 3 provided with a central orifice by which said member may be pivoted upon its complementary member 50 hereinafter described. Said plate is provided with a longitudinal extension 4 offset from the longitudinal axis of the tool having an outer head 5 adapted to clamp against the complementary head 5' on the opposite 55 member of the tool; said extensions are provided with longitudinal grooves 6, regis-

tering with each other and transverse grooves 7 likewise registering, both of which are designed to clamp upon a wire. Said plate 3 is provided with a laterally extending 60 bifurcated claw 8. Adjacent to the plate 3 the shank 1 is provided with a longitudinal groove or recess 9 upon the face opposite to the complementary shank in which the blade 11 may recess when the members are 65 brought into closed relation.

As shown in the drawings, the plate 3 is cut out to form a flush joint with the opposite plate 3' which is likewise cut out, thus forming complementary sockets for said 70 parts.

The opposite member 12 is formed substantially identical with the member just described, with the exception that it is provided with a laterally extending driving 75 head 13 opposite the claw 8, and as previously stated, is provided with a cutting blade 11 on the shank registering with the slot 9.

As is also shown in the drawing, the ad- 80 jacent faces of the shank members are transversely scored at 14 for the purpose of forming a clamping surface for grasping wires.

The tool thus described, as will be readily appreciated, forms a compact and composite 85 nail and staple driver, nail and staple puller, wire cutter and plier and wire tightener of unusual strength and utility.

Having thus described my invention, what I claim as new and desire to be secured by 90 Letters Patent, is—

1. A tool of the character set forth, comprising pivotally connected members having handle shanks and projecting work-engaging elements, and a cutting blade carried by one 95 member, the other member having a channel to receive the blade when the handle shanks are together, said blade thereby constituting a cutter when the handle shanks are separated and relatively moved toward each 100 other and also constituting a holding means for preventing relative lateral displacement of the handle shanks when the handles are together and certain of the work-engaging elements are employed.

2. A tool of the character set forth, comprising pivotally connected members having handle shanks provided respectively with co-operating work-engaging elements that are relatively movable when the handle shanks 110 are relatively moved, said members also having work-engaging elements for use when

the shanks are together and relatively immovable, and a cutting blade carried by the inner side of one of the members adjacent to its pivot connection and extending longitudinally of the handle shank of said member, the opposing portion of the other member having a longitudinally disposed channel to receive the blade when the handle shanks are together, said blade there-
5 by constituting a cutter when the handle shanks are separated and relatively moved
10

toward each other, and also constituting a holding means for preventing relative lateral displacement of the handle shanks when the handles are together and certain of the 15 work-engaging elements are employed.

In testimony whereof I have affixed my signature in the presence of two witnesses.

LEE SPRINGER.
